UNITED STATES PATENT OFFICE.

HERBERT MIDGLEY, OF WORCESTER, MASSACHUSETTS.

DETACHABLE HANDLE FOR HAND-CARDS.

1,104,531.

Specification of Letters Patent. Patented July 21, 1914.

Application filed October 12, 1912. Serial No. 725,375.

To all whom it may concern:

Be it known that I, HERBERT MIDGLEY, a citizen of the United States, residing at Worcester, in the county of Worcester and 5 State of Massachusetts, have invented a new and useful Detachable Handle for Hand-Cards, of which the following is a specification, reference being made therein to the accompanying drawings.

10 My present invention relates to hand-cards such as are employed for stripping or clearing fiber from the cylinders of carding engines, and for similar purposes; and consists in a detachable metal handle and the 15 manner of combining the handle with the base or back-board of the card; the object of the invention being to provide a convenient and efficient metal handle that can be readily attached to and detached from the cards; 20 that will accommodate varying widths, and may be used on different card bases or backs; also to afford a handle device that is simple to assemble and attach, and that will hold 25 in place rigidly and strongly and not be liable to become loose, nor to pull off from the card while in use.

Another object is to provide a handle construction for hand cards of the character described, wherein the metal handle may be 30 manufactured as a separate article from the card body, and which will also permit of the cards themselves being manufactured and sold separately and without attached handles; and of their being packed for shipment 35 in comparatively small space and in very compact arrangement; the handle, or handles, being subsequently assembled upon the cards as required for use; a single handle sufficing for any number of cards as the latter 40 become successively worn out in service.

Another object is to provide a handle that will afford a good and secure grip, and will not slip in the hand; also that will prevent the back or base of the card from warping 45 or straightening out of its original shape.

These objects I attain by means such as explained in the following detailed description, and illustrated in the drawings, wherein—

50 Figure 1 represents a top view of a hand card provided with a detachable handle mechanism illustrating my invention. Fig. 2 is a part side part sectional view of the same. Fig. 3 represents the forward edge 55 of the back-board or base of the card, showing the under cut recesses therein into which

the handle is secured. Fig. 4 is a fragmentary perspective view showing the recess in the rear edge of the card back. Fig. 5 is a bottom view of the sliding sleeve member separate from other parts. Fig. 6 is a front end view of the same, and Fig. 7 is a transverse section at line X X.

Referring to the drawings, the numeral 3 indicates the hand-card composed, in the instance shown, of a base or back 1 of fiber-board or other suitable stiff material, slightly curved transversely and longitudinally straight; a face - clothing 2 provided with carding teeth set therein; and metallic 60 binding strip or frame 4 overlocking and uniting the edges of the back and face plies, and forming a rigid edge therefor. This 65 manner of constructing the body of a hand-card has been heretofore employed and is 70 not in itself a feature of my present invention, and is claimed only as a hand card element in the combinations defined in the 75 claims.

In accordance with my invention, for use 80 with a hand-card and separable therefrom, I provide a metal handle, which is preferably constructed as shown. It comprises a brace or body member 5 having a forwardly extending arm or bifurcated portion 6, the 85 under side of which is adapted to seat against and support the back of the card, while the rear end of said brace is formed as a backwardly extended stem or screw-threaded shank 7. At its front end the brace 90 is furnished with downward lugs or means 9, to interlock or engage with an under-cut seat or recess 10 formed in the edge of the back-board 1, and through the metal border strip 4, a portion of which latter extends 95 across the top of the recess and serves as a strengthening reinforce therefor, as at 11 Fig. 4. The recesses 10 are best notched into the binding-frame 4 in such manner that the end of the recess presents a shoulder in the frame metal that fits the side of the brace-lug, affording endwise support for 100 the card within the handle.

A sleeve member 12 is arranged to slide 105 upon the shank 7, and provided at its forward end with projecting horns or portions 13, having under inclined surfaces 14 that co-act with upwardly inclined surfaces 15 formed upon the body or brace 5. Said sleeve is also formed with a transversely disposed beveled under lip 16 adapted for engagement with an under cut or beveled re- 110

cess 17 formed in the rear edge of the back of the card. The rear part of the sleeve is best made cylindrical, and preferably has a portion of its surface knurled. A nut 19 is arranged upon the screw-threaded shank, abutting against the end of the sleeve 12 and adapted for forcing the sleeve forward and clamping the back of the card firmly between the lugs 9 and the lip 16, when the nut 13 is screwed up. At the same time the inclined surfaces 14 and 15, acting against each other, causes the brace 5 to press firmly against the outer curved surface of the card; thereby holding the handle and card together in strong rigid connection. The nut 19 is best made slightly less in diameter than the end of the sleeve 12, and with a portion of its periphery checked or knurled, its sides being slabbed off for receiving a wrench, as indicated in Figs. 2 and 7.

20 indicates an internally threaded handle-grip member that screws onto the shank 7 and against the nut 19, serving as a check therefor, and as the hand-piece of the handle. The exterior of this hand-piece is best knurled or checked, as shown, to afford a sure hold thereon and prevent its slipping from the hand of the operator while in use. The hand-grip piece 20 is best made with a 30 hollow cylindrical end portion 21 that extends forward over the nut and telescopes with the end of the sleeve 12, thereby inclosing the nut and forming a close joint with the sleeve for excluding dirt from the interior. The rear end of the hand-piece is preferably chambered, and a wooden or non-metallic plug 23 is firmly inserted therein, while a hole or holes 24 are formed laterally through the metal shell affording facility for 35 tacking on a leather strip (not shown) wound about the end of the handle, to form an enlarged end, which is sometimes desired by some operators.

25 indicates a screw stud arranged in the 45 under side of the sleeve 12, and which serves for attachment of a loop or strap through which the hand or fingers may be inserted; such strap being desired by some operators. As the use of a loop or strap upon a hand-card is not in itself new, the strap has not 50 been shown in the drawings.

It may be noted that the handle takes hold at three places on the edges of the card, thus affording firm lateral rigidity; while the under cut bevels and vise-like grip upon the 55 edges of the same draws the back up to the curved brace, thereby tending to hold the back in proper shape and prevent its warping or straightening out; furthermore the 60 handle will not pull off from the back of the card.

A single handle of the construction shown, will outlast quite a number of cards. It can be readily shifted from the old or worn out 65 card to a new one, by turning back the grip-

member 20 and loosening the nut 19 upon the threaded shank 17, so as to let the sleeve 12 move back thereon, thus disengaging the clamping lugs and releasing the back of the card therefrom. The new card can then be 70 inserted and secured by a reverse of this operation. The invention also permits of the handles and cards each being manufactured and sold as a separate article of manufacture, and assembled by the user as desired. 75 Such method greatly facilitates the shipment and distribution, and effects ultimate economy in the production and use of hand-cards of this character.

What I claim and desire to secure by Letters Patent, is—

1. In combination with a hand-card comprising a face-clothing, a backing base and narrow rim reinforce binding the edges thereof and having card-teeth adapted for stripping flats and cylinders of textile-carding machines; a separably attached handle of the character described, having a body member extending across and seating against the back of the card and means for clamping and retaining it upon the base of the card, said retaining means comprising under-locking bevel-faced lugs upon the handle members, and engaging under-beveled recesses cut in the narrow rim of the card base, said parts 90 adapted for gripping the opposite edges laterally across the card and simultaneously forcing the attached portion of the handle to hug down against the back surface of the card, by the co-action of the engaged beveled surfaces, when the clamping means is tightened.

2. In combination as described, with a hand-card comprising a face clothing with card teeth, a thin slightly curved stiff back-board and a metal binding frame uniting the edges of said face clothing and back-board, the front and rear edges of said card being provided with under beveled recesses cut through said binding frame, as shown; and the detachable metal handle consisting of a bifurcated brace having an extended shank, the under surface of the brace arms being adapted to seat against and support said back-board, and having lugs that engage in said under-beveled recesses, a sleeve mounted upon said shank and having projections that coact with counter-matching projections upon said brace for maintaining the alinement relation, and provided with an under beveled lip that engages the opposite recess in said frame, means for adjusting and holding said sleeve for clamping the parts, and a hand-grip member arranged upon said shank.

3. The combination, of a hand-card including a face clothing having card-teeth therein, a thin curved back member, and a metallic binding strip overlocking and uniting the edges thereof, said card having at its 130

- front and rear edges, engaging recesses formed through the metal binding frame and under-beveled in the back-member adjacently above the face clothing, said metallic strip being notched, but extending continuously across the tops of said recesses; a separably attached handle comprising a back-supporting brace, a sleeve slidably mounted thereon and having intermatching members that maintain relative alinement with said brace, the brace and sleeve being provided with lugs that fit in the notched frame and engage in the under-cut recesses at front and rear of the card, a nut acting against said sleeve for tightening the brace upon the card, and a hand-grip member mounted upon the extended rear part of said brace.
4. A handle for hand-cards, comprising a body member having an engaging lug at one end and a screw-threaded shank at its other end; a sleeve slidable upon said shank, and having a projecting under lip, said sleeve provided with inclined members that match upon upwardly inclined surfaces on the body, and an internally threaded member fitted upon said screw-threaded shank and abutting against said sleeve.
5. A detachable handle for hand-cards, comprising a furcated brace or body having an extended shank, and provided with under-engaging lugs at the ends of its fork members, and upwardly inclined surfaces on its body, said brace adapted to seat against the back of the card, a member slidable upon said shank and provided with means for engagement with the rear edge of the card, and inclines for engaging said inclined surfaces upon the brace body, a nut threaded upon the shank and abutting against said
- sliding member, and a hand-grip member mounted upon said shank and abutting against said nut.
6. In a handle for hand-cards, the combination, of a dual-armed card-supporting brace, its body provided with a screw-threaded shank, the two arms having under-beveled card-engaging lugs at their outer ends, a sleeve having a transverse forwardly beveled under engaging lip, and a cylindrical rear end slidably mounted upon said shank at its junction with the body, means for maintaining the relative alinement of the sleeve and body members, a nut threaded upon said shank and abutting against the end of the sleeve, and an internally threaded hand-grip member having chambered ends rotatively mounted upon the shank at the back of said nut and fitted to screw up against the same, substantially as set forth.
7. In an adjustable attachable handle for hand-cards, the combination with the brace having the threaded shank, the sleeve slidably on said shank, having an under engaging lip, upwardly inclined forwardly projecting horns, and cylindrical rear end; and a nut threaded upon the shank and bearing against the end of said sleeve; of the internally threaded hand-grip member rotatable upon said threaded shank to screw against said nut as a check, and having a forward hollow cylindrical extension that incloses said nut and telescopes with the end of said sleeve, for the purpose set forth.

Witness my hand this 9th day of October, 1912.

HERBERT MIDGLEY.
